CLAIM

The ornamental design for a terminal printer cover, or the like, substantially as shown and described.

DESCRIPTION

FIG. 1 is a right front perspective view of a terminal printer cover, or the like, showing our new design;
FIG. 2 is a left front perspective view thereof;
FIG. 3 is a left rear perspective view thereof;
FIG. 4 is a right rear perspective view thereof;
FIG. 5 is a front perspective view of a second embodiment of our new design;
FIG. 6 is a rear perspective view thereof;
FIG. 7 is a top plan view thereof on an enlarged scale; and
FIG. 8 is a bottom plan view common to both embodiments.

FIG. 1
